UNITED STATES PATENT OFFICE.

WILLIAM B. HAYDEN, OF NEW YORK, N. Y.

DESIGN FOR A TILE.

SPECIFICATION forming part of Design No. 23,391, dated June 19, 1894.

Application filed May 26, 1894. Serial No. 512,570. Term of patent 14 years.

To all whom it may concern:

Be it known that I, WILLIAM B. HAYDEN, a citizen of the United States, residing at New York city, in the county of New York and State of New York, have invented or produced a new and original Design for Tiles, of which the following is a specification.

The object of this design is to provide a novel and ornamental top surface or face for a sidewalk tile which presents a handsome and distinguishing appearance to the eye; and to accomplish this object, the design consists in a tile having its face provided with ornamentation composed of a series of concentric lines inclosed by a rectangular or square figure which is surrounded by a series of ornamental lines.

The design is illustrated by the accompanying drawing, in which the figure is a perspective view, showing the new ornamentation of the top surface of a tile.

As here illustrated the tile is in the form

of a rectangular block or brick 1, and the top surface or face of this block is provided with a series of concentric lines 2 bounded by a rectangular or square border, or figure 3, which latter is surrounded by a series of ornamental lines 4. The ornamental lines at each side of the rectangular or square border 3 are shown as rectilinear and parallel.

The design is shown duplicated at each end portion of the top surface of the tile.

Having thus described my invention, what I claim is—

The design for a tile, substantially as shown and described.

In testimony whereof I have hereunto set my hand and affixed my seal in presence of two subscribing witnesses.

WILLIAM B. HAYDEN. [L. S.]
